EDWARD G. BUDD, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

WINDOW.

1,170,874.

Specification of Letters Patent.

Patented Feb. 8, 1916.

Original application filed November 13, 1908, Serial No. 462,366. Divided and this application filed April 11, 1912. Serial No. 690,106.

To all whom it may concern:

Be it known that I, EDWARD G. BUDD, a citizen of the United States, residing at Philadelphia, in the county of Philadelphia and State of Pennsylvania, have invented certain new and useful Improvements in Windows, of which the following is a specification.

This invention relates to windows having metallic sashes and adapted for use in buildings and railway cars. The invention is directed to the provision of an improved means for securing the glass or other panel of a window to the metallic sash.

The object of the invention is to provide such a securing means which will hold the parts rigidly throughout a long period of use, which may be manufactured and assembled at low cost and which permits of removing the panel when such removal is desired.

The preferred embodiment of the invention is illustrated in the accompanying drawings in which—

Figure 1 is a front view of a window sash broken away in part, Figs. 2, 3 and 4 are transverse sections through the top, bottom and side members of the sash, respectively, and Figs. 5 and 6 are detail sectional views showing the securing means.

Fig. 1 shows a window sash having a metallic frame and a panel of glass 8 secured within the same. The sash is preferably of rectangular form and consists of four frame-members secured together at their ends. As shown in Figs. 3 and 4, each frame-member may consist of a single strip of sheet-metal pressed to the cross-sectional shape illustrated in those figures. At one edge of the strip a flange 7 is provided and at the other edge a fold 6 which incloses the flange 7 so as to unite the edges of the strip of metal and to provide upon the frame-member a flange extending forwardly of the sash. The frame-member illustrated in Fig. 2 is formed of two strips of sheet-metal and this construction may be used for all of the frame-members if desired.

Referring now to the means for securing the pane of glass within the sash, the glass is positioned on one side by the inwardly extending flange on the frame, consisting of the folds 6 and flanges 7. To hold the pane of glass on the opposite side, I provide retaining strips 18, consisting of strips of sheet-metal pressed to a substantially U-shaped cross-section, as shown in Figs. 2, 3 and 4. This strip is secured in position by means of screws 19 coating with the frame-members. For this purpose, the retaining strips 18 are provided with raised pads 20 at intervals throughout their length to form seats for the heads of the screws 19. As the sheet-metal employed in the construction of the frame-members is quite thin, the retaining strips 18 would not be fastened to the frame-members sufficiently securely if the screws 19 engaged threads formed in openings in the frame-members, since the retaining strips 18 are subjected to considerable strain, particularly in windows for railway-cars. For this reason, I provide additional devices for receiving the threaded ends of the screws 19. Threaded openings are formed in the sheet-metal frame-members at intervals along the length of the retaining strips 18 and in each of these openings I provide a nut 21 threaded both interiorly and exteriorly. This nut is provided with a head 22 having flattened sides and of such dimensions that the distance between opposite flattened sides is the same as the distance between the side-walls of the retaining strips 18.

In assembling the parts, the nuts 21 are screwed into the threaded openings in the frame-members until the heads 22 of the nuts engage the frame-members and the nuts are brought to such positions that two of the flattened sides thereof lie parallel to the length of the frame-member, as shown in Fig. 5. When the pane of glass 8 is positioned against the folds 6, its edge being preferably provided with a soft gasket 23, the retaining strips 18 are positioned on the opposite side of the pane of glass and pressed against the frame-member so that the side-walls thereof straddle the heads 22 of the nuts 21. The screws 19 are then inserted through the openings in the pads 20 and screwed into the interiorly threaded openings in the nuts 21 until they hold the retaining strips 18 firmly upon the frame-members. By this construction, side strains on the retaining strips 18 are taken up by the heads 22 of the nuts 21 and transmitted directly to the frame-members by the nuts 21 and independently of the screws 19. The

main function of the screws 19, therefore, is merely to hold the retaining strips down upon the frame-members and the principal strains on these screws are in the direction 5 of the length of the screws. The construction therefore possesses very considerable strength and good wearing qualities, since the screws 19, which are quite small, are relieved of substantially all of the side pressure 10 on the retaining strips 18.

Having described my invention, what I claim as new therein and desire to secure by Letters Patent of the United States is:

1. In a window, a metallic frame having 15 an inwardly extending flange, a pane of glass positioned by said flange, fastening strips for holding the pane in position, screws for securing said strips to the frame and nuts secured in openings in the frame 20 underlying said strips and provided with threaded openings to receive the ends of said screws, said strips having side walls and nuts having flattened heads interposed between and in contact with the side walls of 25 said strips to brace the strips against side strains independently of the screws, substantially as set forth.

2. In a window a metallic sash frame having a forwardly-extending flange and a portion 30 at right angles thereto, a fastening strip of U-shaped sheet-metal in inverted position upon said frame portion, a pane of glass having one edge positioned against said frame portion between said flange and strip

and held thereby, screws for holding said strip to the frame, extending through the same and said frame portion, nuts screwed into threaded openings in said frame portion and each provided with a threaded opening to receive the end of one of said 4 screws, said nuts having heads having flattened sides filling the space between and in contact with the side walls of the said strip, to brace the latter against side strains independently of the screws, substantially as set 4 forth.

3. In a window a metallic sash frame having a forwardly-extending flange and a portion at right angles thereto, a fastening strip of U-shaped sheet-metal in inverted position 5 upon said frame portion, said strip having raised screw-seats thereon, a pane of glass positioned with one edge between said flange and strip, screws extending through said strip, and nuts secured to said frame portion 5 and having threaded openings therein to receive the ends of said screws, said nuts having plane surfaces positioned between and in contact with the side walls of said strip, to brace the latter against side strains, substantially as set forth.

This specification signed and witnessed this 22nd day of March, 1912.

EDWARD G. BUDD.
